UNITED STATES PATENT OFFICE.

FRANCIS A. WILLIAMS, OF NEW YORK, N. Y.

METALLIC RAILROAD-TIE.

SPECIFICATION forming part of Letters Patent No. 235,321, dated December 7, 1880.

Application filed January 2, 1880.

To all whom it may concern:

Be it known that I, FRANCIS A. WILLIAMS, of the city, county, and State of New York, have invented certain Improvements in Metallic Railroad-Ties, of which the following is a specification.

This invention is more particularly intended to be made of cast-iron; and its object is to provide a metallic tie which will have a firm and steady gripe upon the earth or ballasting, in or upon which it is placed, to afford a broad and effective support to the rails, and provide not only for the strong retention of the rails in position, but also for their ready detachment, when required, for replacement or repair.

My said invention comprises a railroad-tie composed of two broad bearing-plates, each having cast or formed thereon peculiarly-constructed lugs, arranged to act in conjunction with sliding keys, by which the rails are to be attached to the tie, the two plates being connected by vertical flat ribs, which project downward not only between the plates but underneath the same, so that the ballast of the road-bed is enabled to firmly anchor the tie as a whole in its place.

Figure 1 is a plan view, Fig. 2 an inverted plan view, Fig. 3 a vertical longitudinal sectional view, and Fig. 4 an end view, of a railroad-tie embracing my said invention.

A A are the bearing-plates, the edges of which may be beveled, as shown at a, and preferably formed with downwardly-extending circumferential flanges b. B B are the longitudinal ribs which connect the plates A A. The vertical depth of these ribs is much greater than their horizontal width, in order to afford the greatest resistance to vertical strain. These ribs B B are at some distance apart, the plates A A being at opposite ends of the ribs, and being connected thereby, as represented in Figs. 1, 2, and 3, the end portions, c, of the ribs projecting downward from the plates, while the central portions, b, also projecting downward, have between them the space C.

When the tie is placed in position and suitably ballasted the end portion, b, serves to anchor the plates fixedly in their horizontal

position, while the earth or ballasting, being firmly rammed or packed between and around the central portions, b, assists in this retention of the bearing-plates in position, and serves to steady and support them in their requisite relation with the rails D D.

Upon each of the bearing-plates A A is a lug, g, so shaped as to fit over the adjacent flange of the rail placed upon the plate, as more fully represented in Fig. 3. Upon each of the plates, also, and arranged opposite to its lug g, are two other lugs, h, so shaped as to hold upon the opposite flange of the rail when the rail is thrust endwise between the lug g on one side and the lugs h on the other.

The inner edges or sides of each pair of lugs h are shaped to form guides a', in which is placed a sliding key, m, the inner end of which sliding key being so shaped as to pass over and upon the adjacent flange of the rail and to gripe the same in proportion to the degree with which the said key is forced inward toward the rail.

Transverse slots n are formed in the lugs h, and a corresponding slot is formed in each of the keys m, a locking-wedge, r, being driven through the slots, and, bearing against the innermost surface of the slot in the key m, forces the said key over and upon the flange of the rail, and lock the rail firmly between the inner end of the said sliding key and the fixed lug g on the opposite side of the rail, as more fully indicated (in part in dotted outline) in Fig. 1.

It is to be understood that the plates A A, ribs B B, and lugs g h are preferably to be cast in one piece.

I do not in this present application claim the lugs g h, sliding keys m, and locking-wedges r, formed upon disconnected plates for attachment to wooden ties, and with the object of providing a bearing to the joints of rails, it being my intention to make a separate and independent application for Letters Patent on the aforesaid parts for the purpose last herein indicated.

What I claim as my invention is—

The metallic railroad-tie composed of the two broad bearing-plates A A, each having cast or formed on its upper surface the lugs g

and *h*, the flat ribs *B* *B*, connecting the bearing-plates and projecting downward in vertical planes below as well as between said plates, and with a space between said ribs, 5 and the sliding keys *m*, placed upon the upper sides of the bearing-plates and movable in a direction longitudinal with the ribs, all

substantially as and for the purpose herein set forth.

FRANCIS A. WILLIAMS.
